(57) **CLAIM**

I claim the ornamental design for a portable speaker system, as shown and described.

DESCRIPTION

FIG. 1 is a top, front isometric view of a portable speaker system, showing my new design;

FIG. 2 is a top, rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

All of the broken lines shown, including the two front circular speaker grills seen in FIGS. 1 and 3, are included for the purpose of illustrating portions of the portable speaker system that form no part of the claimed design.
